(57) **CLAIM**

The ornamental design for a perforated label, as shown and described.

DESCRIPTION

FIG. 1 is a top isometric view of a perforated label, showing my design;

FIG. 2 is a top-plan view of the perforated label;

FIG. 3 is a bottom plan view of the perforated label; and, FIG. 4 is a bottom isometric view of the perforated label. The longer dashed broken lines shown in FIGS. 1, 2, 3, and 4 are perforation lines and form part of the claimed design. The shorter dashed broken lines shown in FIGS. 3 and 4 show environmental structure that does not form part of the claimed design.
